UNITED STATES PATENT OFFICE.

ROBERT W. WIEDERWAX, OF ATLANTIC CITY, NEW JERSEY, ASSIGNEE OF ONE-HALF
TO CARLTON GEIST, OF ATLANTIC CITY, NEW JERSEY.

AIR AND GAS MIXING DEVICE.

1,295,247.

Specification of Letters Patent. Patented Feb. 25, 1919.

Application filed June 10, 1918. Serial No. 235,205.

To all whom it may concern:

Be it known that I, ROBERT W. WIEDERWAX, a citizen of the United States, residing at Atlantic City, in the county of Atlantic 5 and State of New Jersey, have invented certain new and useful Improvements in Air and Gas Mixing Devices, of which the following is a specification.

My invention relates to air and gas mixing devices, for use in connection with burners.

An important object of the invention is to provide means of the above mentioned character, having parts which are readily 15 adjustable for effecting the combination of the proper relative volumes of air and gas, with the gas supply valve partly or wholly open.

A further object of the invention is to 20 provide apparatus of the above mentioned character, having a large range of adjustment, to obtain a perfect gaseous fuel or mixture.

A further object of the invention is to 25 provide means to effect an automatic control and mixture of a perfect gas supply under all conditions, by the turning of a single crank or element.

A further object of the invention is to 30 provide apparatus of the above mentioned character which is simple in construction, inexpensive to manufacture, and may be conveniently adjusted.

Other objects and advantages of the invention will be apparent during the course 35 of the following description.

In the accompanying drawings forming a part of this specification and in which like numerals are employed to designate like 40 parts throughout the same,

Figure 1 is a side elevation of apparatus embodying my invention,

Fig. 2 is a central vertical longitudinal section through the apparatus, parts in elevation,

Fig. 3 is a front elevation of the device,

Fig. 4 is a front elevation of the valve plate and associated elements, showing the air opening closed or covered, and,

Fig. 5 is a similar view showing the air opening uncovered.

In the drawings, wherein for the purpose of illustration is shown a preferred embodiment of my invention, the numeral 5 designates a gas manifold, having connection

with a suitable source of gas. Any suitable number of my air and gas mixing devices may be connected with the gas manifold 5 and for the purpose of illustration only one device will be described.

My air and gas mixing apparatus comprises a main casing 6, which is preferably cylindrical and horizontally arranged. This casing is provided upon its lower side with a tubular extension or neck 7, having a flange 8, arranged upon a flange 9, and detachably secured thereto by screws 10 or the like. The flange 9 is formed upon a tubular neck or extension 10', carried by the gas manifold 5.

One end of the casing 6 is covered by a plate 11, detachably secured thereto by screws 12 and which is used as a clean out plate. The opposite end of the casing 6 is covered by a removable plate or head 13, having a segmental air supply opening 14, formed therein. This plate 13 has an annular flange 13', receiving one end of the main casing 6, and screws 14', serve to detachably secure the flange to the casing. The numeral 15 designates a rotatable valve plate, having an annular flange 16, pivotally receiving the annular flange 13'. The valve plate 15 has a segmental opening 17, formed therein, adapted for movement into and out of registration with the opening 14.

The numeral 18 designates an upper casing, preferably horizontally arranged and connected with the lower casing 16, by means of a tubular portion 19. One end 20. 90 of the upper casing 18 is adapted for connection with a burner or burner tip or with a pipe leading to the same, while the opposite end of the casing 18 is open and is covered by a plate 21, detachably secured thereto by screws 22 or the like.

Arranged within the casing 6 is a horizontal valve 23, embodying a casing 24, which is connected with vertical pipes 25 and 26, as shown. The lower end of the pipe 26 has screw-threaded engagement within an opening 27, formed in the flange 9, and affords an air tight junction therewith. The valve 23 embodies a valve element 28, held seated by a spring 29, engaging a washer 30, held in place by a screw 31, engaging the valve element 28. A stop 32, operates within a slot 33 in the valve casing 24, and limits the movement of the valve element 28. The valve element 28 is turned by a stem 34, hav-

ing a handle or crank 35 rigidly secured thereto. The valve stem is pivotally mounted within an opening 36, formed in the plate 13 and the valve plate 15. The valve plate 15 is free to turn upon the stem 34.

Rigidly secured to the stem 34 is a crank or arm 37, having a head 38, provided with a screw-threaded opening, receiving a pin 39, having a head 40, to turn the same. The 10 pointed end of the pin is adapted for insertion within a selected recess or depression 41, a series of which is formed upon the outer face of the valve plate 15 near its periphery. It is thus apparent that the stem 15 34 turns the valve element 28 and the valve plate 15 simultaneously and that by manipulation of the screw 39 the valve plate may be adjusted independently of the valve stem 34, for obtaining the proper relative volume 20 of air and gas.

The numeral 41' designates an adjusting gas valve, as a whole, embodying a casing 42, having an outlet opening 43, which is partly or wholly closed by an inlet valve 44, 25 having screw-threaded engagement with the rear end 45 of the casing 42. This inlet valve has a stem 46 extending through a central opening in the plate 21, and forming a substantially gas tight fit therewith, and 30 provided with an exterior head or nut 47 to turn the same. The casing 42 is screw-threaded upon the upper end of the pipe 25, as shown. The gas adjusting valve 41' is mounted centrally within the upper casing 18, as shown.

The operation of the device is as follows: The inlet valve 44 is adjusted to regulate the volume of gas supplied into the casing 18, as may be necessary, depending upon the 40 conditions of each particular case. The valve plate 15 is adjusted with respect to the crank 37 for supplying the proper amount of air which may be needed in each particular case. This permanent adjustment having been made, the crank 35 is swung upwardly or to the right, opening the valve 23, and simultaneously turning the valve plate 15 but not sufficiently to uncover the opening 14. The crank 35 is so arranged and synchronized with the adjusting gas supply valve 41' and the valve plate 15, that gas alone will first pass to the burner and be ignited, prior to the introduction into the burner of air. One movement of the crank 50 35 uncovers the opening 14 and air in sufficient quantities is supplied to the gas, to produce a gaseous fuel, lean or rich as may be desired. This gaseous fuel passes to the burner and is of course controlled in volume 55 by the manipulation of the crank 35, as is obvious. In use, the crank 35 controls automatically the supply of gas and air and no adjustments are necessary, the crank 35 supplying the proper mixture at all times.

60 The adjustments are made in advance of

the use of the device, by the manipulation of the gas supply needle valve 41' and the valve plate 15. These are then synchronized by the crank 35 and the crank 35 thereafter absolutely and wholly controls the operation 70 of the device in one movement. By this synchronized adjustment gas flows first alone, because the gas port opens first as the crank is moved, not as a result of two movements of the crank, and as the device is closed off, 75 the air supply closes first, so that the explosions are avoided both in lighting and shutting down the device.

It is to be understood that the form of my invention herewith shown and described is 80 to be taken as a preferred example of the same, and that various changes in the shape, size, and arrangement of parts may be resorted to without departing from the spirit of the invention or the scope of the sub- 85 joined claims.

Having thus described my invention, I claim:

1. A device of the character described, comprising a casing, a pivoted valve plate 90 to control the passage of air into the casing, a valve to control the supply of gas to the air within the casing, a member to operate the valve, and an adjustable device serving to positively connect the member and valve plate 95 whereby the valve plate is turned in opposite directions by the member, said device upon adjustment permitting of the turning of the pivoted valve plate with relation to said member.

2. A device of the character described, comprising a casing having one end provided with an air inlet, a pivoted valve plate having an annular flange to receive the said end of the casing and having an opening adapted for movement into and out of communication with the air inlet, said pivoted valve plate being provided near its center with a pivot opening and near its periphery with a set of spaced depressions, a gas valve arranged within the casing and having a stem projecting through the pivot opening, means to turn the stem, a crank secured to the stem, and an element having screw-threaded engagement with the crank 105 and adapted to have one end thereof inserted within a selected depression.

3. A burner of the character described, comprising a casing, a gas valve associated therewith, a pivoted valve plate carried by one end of the casing, a stem to turn the gas valve and extending centrally through the valve plate and arranged at substantially a right angle thereto, a crank carried by the stem and extending substantially radially of the valve plate, and an element secured to the crank and engaging the valve plate and adapted to be longitudinally adjusted with relation to the crank.

4. A burner of the character described,

comprising a casing, a gas valve associated therewith, a pivoted valve plate carried by one end of the casing, a stem to turn the gas valve and extending substantially centrally through the valve plate and arranged at substantially a right angle thereto, a crank carried by the stem and extending substantially radially of the valve plate, and an element having screw-threaded en-

gagement with the end portion of the crank 10 and adapted to be moved into and out of holding engagement with the valve plate.

In testimony whereof I affix my signature in presence of two witnesses.

ROBERT W. WIEDERWAX.
